UNITED STATES PATENT OFFICE.

PIERRE I. CHANDEYSSON, OF ST. LOUIS, MISSOURI, ASSIGNOR OF ONE-HALF TO SAMUEL W. FORDER AND W. CARVER FORDER, OF ST. LOUIS, MISSOURI.

CAB SIGNAL SYSTEM.

966,796.

Specification of Letters Patent.

Patented Aug. 9, 1910.

Application filed April 5, 1909. Serial No. 488,025.

To all whom it may concern:

Be it known that I, PIERRE I. CHANDEYSSON, a citizen of the United States, and a resident of the city of St. Louis and State of Missouri, have invented a new and useful Improvement in Cab Signal Systems, of which the following is a specification.

My invention relates to the class of devices commonly known as cab signal systems, that is, signaling devices mounted in the cab or other portion of a train in electric circuits whose currents are controlled by devices located on or adjacent to the track.

The object of the invention is to secure certainty in the action of the system, and to give certain notice in case any portion of the system becomes deranged.

To these ends, the invention consists in the arrangements and combinations herein-after described and claimed.

In the accompanying drawing, which forms part of this specification, and wherein like symbols refer to like parts wherever they occur, Figure 1 is a diagram of a rail-way track equipped according to my invention; Fig. 2 is a diagram of the portions of my system that are movable with the train, and showing also a transverse paramagnetic tie arranged transversely to the rails and a solenoid surrounding said tie; Figs. 3 and 7 are diagrammatic views of portions of a track equipped according to my system, but each figure involving certain modifications hereinafter more fully described; Figs. 4, 5 and 6 are diagrammatic views of modified forms of cab signal circuits, each of which is hereinafter more fully described.

Extending crosswise of the railway track at suitable places are ties or bars 1 of iron or other suitable paramagnetic material, which bars support or are secured to the rails 2. Surrounding each of these ties or bars is a solenoid 3 whose terminals are connected respectively to the insulated rails of a distant block of the track. The rails of each block are electrically connected by a wire 4 containing a battery 5 or other suitable source of electrical energy. By this arrangement, the tie or bar 1 serves as the core of the solenoid or electromagnet and the rails in contact with the ends of said bar become the poles of said electromagnet.

Surrounding one of the axles of the locomotive or other vehicle is a solenoid 6 in a closed circuit 7 containing a battery 8, a

polarized electromagnet or relay 9 and an ammeter or other indicator 10 which is located in the cab or elsewhere for convenient observation. Preferably, an inductive resistance coil 11 is arranged in a multiple arc 6c 12 of said circuit 7 in parallel with the polarized relay 9.

Located in the cab or elsewhere on the train for convenient observation are two electric lamps 13, 14 mounted in parallel 65 arcs 15, 16 of a circuit 17 containing a battery 18 and the armature 19 of the polarized electromagnet or relay 9. Said armature 19 is permanently connected to the battery of the cab-circuit 17 and its stops 70 are the terminals of the arcs 15, 16 containing the respective lamps which constitute the principal signals or indicating devices. The armature 19 is adapted to swing from one stop to the other according as one or the 75 other pole of the polarized electromagnet or relay 9 becomes effective for the purpose. Under normal conditions, however, the armature 19 remains against whichever one of its stops it happens to be in contact with 80 when the normal track conditions are resumed. The function of the polarized electromagnet or relay 9 and its armature 19 is to determine through which of its arcs 15, 16 the cab signal circuit 17 shall be completed. This function is accomplished by 85 variations of the current that energizes the polarized electromagnet or relay 9, and these variations in turn are effected by the condition of the track solenoid 3. 90

The operation of the system above described, which is illustrated in Figs. 1 and 2, is as follows: The normal current in the polarized relay 9 has a tendency to cause its armature 19 to be drawn toward a particular one of its stops; but this normal current is not strong enough of itself to pull the armature of the relay away from the other contact stop, when said armature happens to be against such other stop. 95 When the axle solenoid 6 approaches a tie or bar 3 of paramagnetic material, the number of lines of force through axle solenoid 6 will increase, for the reason that said bar closes the normal gap in the magnetic circuit and completes an all metal circuit; and under these conditions, the normal current of the battery will decrease. Therefore, if the armature 19 of the polarized relay 105 happens to be on the contact to which the 110

red light 14 is connected, it will remain there; and if the armature happens to be on the contact to which the white light 15 is connected, it will remain there. When the 5 axle solenoid 6 recedes from the tie or bar of paramagnetic metal, the number of lines of force through the axle solenoid will decrease and an electromotive force of the same direction as that of the battery 8 will be 10 induced thereby; and, therefore, the normal current of the battery 8 will be increased sufficiently to attract its armature 19 against the contact to which the red light 14 is connected. In this case, the tie or bar of 15 paramagnetic metal acts merely as a conducting path for the magnetic circuit which includes the axle and the wheels; and the variation of the lines of force in the axle is due to the passive property of the magnetic material 20 of offering a less resistant path for the lines of force created by the magneto-motive force of the axle solenoid. The same effect will be produced whether the tie or bar of magnetic metal is surrounded by a solenoid 25 or not. When, however, a current flows through the track solenoid 3 surrounding the tie 1 of paramagnetic metal, and a train approaches said tie or bar, the number of 30 lines of force threading through the axle solenoid 6 is decreased or reversed in direction. In consequence of this condition, an electro-motive force will be generated in the axle solenoid 6 in the same direction as that of the electromotive force due to the 35 battery 8, with the result that the current of the axle solenoid circuit 7 will be increased above its normal intensity, thereby additionally energizing the polarized electromagnet or relay 9 sufficiently to attract its armature 40 against the contact to which the red light 14 is connected. When the axle recedes from the metal tie or bar 1, an electromotive force will be generated opposite to the normal electromotive force in the axle 45 solenoid circuit 7, and thereby the normal current in said circuit 7 will be not only diminished but reversed, thereby reversing the polarity of the polarized electromagnet or relay 9 and causing it to move its armature 50 against the contact to which the white lamp 13 is connected. This condition indicates that the block corresponding to that particular paramagnetic metal tie is clear. On the other hand, if a train 55 happens to be on the block of track corresponding to the track solenoid 3 of the particular tie or bar 1 now under consideration, the battery 5 of said solenoid is short-circuited by the wheels and axles of the 60 train bridging the space between the rails; and consequently the current in said track solenoid 3 is inappreciable, so that the condition corresponds to the case stated in the last paragraph, and the circuit of the battery 65 18 is completed through the red lamp 14.

It is noted that in the system above described, a failure of the red signal lamp to flash or glow when the train passes a paramagnetic tie or bar indicates that the system is out of order. If the track is clear, 70 the red lamp will glow for an instant while the axle is approaching an energized paramagnetic bar; and the failure of such red lamp to glow for an instant is an indication that the cab part of the signal is out of 75 order. The ammeter or indicator is added as a further means of ascertaining whether or not the cab portion of the signal system is in good working order. The track part of 80 the system is arranged in any usual way wherein any failure of the apparatus will cause the signal to indicate danger.

In the above description of the operation, the ammeter 10 and the inductive resistance coil 11 are not mentioned, as they are not 85 essential to the operation of the system. The indication of the ammeter varies with the current in the circuit 7 and as such affords an intelligible indication of the conditions upon which said current depends; 90 but its principal function is to indicate the strength of the normal battery current in said circuit 7. The function of the inductive resistance coil 11 is to regulate the amount of current through the relay, and to 95 reinforce or oppose the electromotive force generated in the current 7 by induction. As indicated in Figs. 5 and 6, the ammeter may be eliminated; and as illustrated in Fig. 5, the inductive resistance coil may be eliminated. 100

In the track portion of the system illustrated in Fig. 1, each of the track solenoids is connected by wires 20 directly to the rails of the particular block whose varying conditions are to be reflected by said solenoids. In the modification illustrated in Fig. 3, the track solenoid 3 is located in a local circuit 21 containing a battery 22, and an armature 23, through which said circuit 21 is normally closed; and the rails of the block whose conditions are to be reported by said track solenoid are in a normally closed circuit 24 containing an electromagnet 25 which normally holds said armature 23 against its upper stop to close said circuit 21. 110 115

The operation of the system illustrated in Fig. 3 is substantially the same as that illustrated in Fig. 1, the difference being merely such as is incidental to the use of a relay 120 in the line circuit to control a local circuit instead of having the elements of the local circuit in the line circuit.

In the modified system illustrated in Fig. 4, the inductive resistance coil is omitted from the circuit of the polarized relay; a second solenoid 26 is mounted on the axle in a permanently closed circuit 27 containing a battery 28, an ammeter 29, and an inductive resistance coil 30. The operation of this 125 130

modified system is believed to be obvious from the foregoing description of the system illustrated in Fig. 2.

In the modified system illustrated in Fig. 5, the axle solenoid circuit is closed but contains no battery and no instruments except the polarized relay. In this modification, the difference in the electromotive force required to operate the polarized relay depends entirely upon the track conditions, as there is no battery current to augment or oppose the induced current. This Fig. 5 illustrates an arrangement whereby the condition of the track solenoid is controllable by the operator. In this modification, the track solenoid 3 is in a circuit 31 which is provided with a pole changer 32 adapted to be alternatively connected in any usual way to the terminals of a battery 33. As illustrated in Fig. 5, the pole changer is the armature or movable with the armature of an electromagnet 34 in a circuit 35 containing a battery 36 and a manually operable switch or circuit closer 37. When the switch is closed, the electromagnet 34 is energized to attract the pole changer so as to close the current of the battery 33 through the track solenoid 3 in one direction; and when the switch 37 is open, the pole changer is shifted to reverse the current of the battery 33 through said track solenoid 3. The varying conditions of the track solenoid 6 thus brought about are reflected in the axle solenoid and determine the polarity of the polarized relay 9, which in turn determines through which of the two lamps the circuit of the battery 18 shall be completed.

In the modification illustrated in Fig. 6, the circuit of the lamp battery 18 is normally closed through the armature 38 of an electromagnet 39 which electromagnet is located in the circuit 7 of the battery 8. The armature 38 is arranged to drop or be retracted from its forestop and thereby open the lamp circuit whenever the battery 8 becomes excessively weak. It is noted that in the system illustrated in Fig. 6, the solenoid 6 movable with the train is not mounted on an axle but is specially provided with a core 40, which may be mounted in any suitable way. It is also noted that instead of being arranged at right angles to the track, this solenoid 6 and its core are at an angle thereto. Likewise, the track solenoid 3 in this modified system is arranged at an angle to the track and is specially provided with a core 41, which is clear of the rails.

Obviously, instead of lamps, other signaling devices may be used, and the various elements hereinbefore mentioned may be replaced with their electrical equivalents. So, too, instead of insulating the rails at both ends of the tie or bar 3, as illustrated in Fig. 1, it is sufficient to insulate the rail on one side of the track only as illustrated

in Fig. 3. So, too, it is obvious that the conditions of the track solenoid may be varied either positively or automatically and that the devices for effecting such variations admit of a wide range of selection. Therefore, I do not wish to be limited to the details of construction or arrangement hereinbefore described.

What I claim as my invention and desire to secure by Letters Patent is:

1. A railway signal system comprising a normally closed electric circuit mounted on a train and comprising a source of electrical energy and a solenoid surrounding an axle thereof and a paramagnetic bar located in said track in coöperative relation to said solenoid.

2. A signal system comprising a normally closed electric circuit mounted on a movable vehicle and comprising a source of electrical energy and a solenoid surrounding an axle, and a stationary paramagnetic bar arranged transversely below the path of said vehicle in coöperative relation to said solenoid.

3. A signal system comprising a normally closed electric circuit mounted on a movable vehicle and comprising a source of electrical energy and a solenoid surrounding an axle thereof, and a stationary paramagnetic bar arranged transversely below the path of said vehicle, and a controllable circuit comprising a solenoid surrounding said bar.

4. A railway signal system comprising a normally closed electric circuit mounted on a train and comprising a source of electrical energy and a solenoid surrounding an axle thereof, and a paramagnetic bar located in and transversely of the track, a second electric circuit, a solenoid in said second circuit and surrounding said bar, and means for varying the electrical condition of said second circuit.

5. A railway signal system comprising a normally closed electrical circuit mounted on a train and comprising a solenoid surrounding an axle of said train and an indicator, and a paramagnetic bar located in and transversely of the track, a second electric circuit, a solenoid in said second circuit and surrounding said bar, and means for varying the electrical condition of said second circuit.

6. A railway signal system comprising a normally closed electric circuit mounted on a train and comprising a battery and a solenoid surrounding an axle thereof, and a paramagnetic bar located in and transversely of said track in one block thereof, and a solenoid surrounding said bar and electrically connected to the rails of another block of said track, said rails being electrically connected through a source of electrical energy.

7. A railway signal system comprising a normally closed electric circuit mounted on a train and comprising a battery and a solenoid

surrounding an axle thereof, and a paramagnetic bar located in and transversely of said track in one block thereof, an electrical circuit containing a solenoid surrounding said bar, a source of electrical energy connected to the respective rails of another block of said track, and operatively connected to said track solenoid circuit to control the electric current therein.

10. 8. A railway track system comprising a normally closed electrical circuit mounted on a train and comprising a solenoid surrounding an axle thereof, and a paramagnetic bar located in and transversely of the track of one block, and a solenoid surrounding said bar and electrically connected with the respective rails of another block, which rails are electrically connected with each other and a source of electrical energy in such connection.

9. A railway track system comprising a normally closed electric signal controlling circuit mounted on a train and comprising a solenoid surrounding an axle thereof and means for magnetizing said axle, and a paramagnetic bar located in and transversely of said track of one block, the solenoid surrounding said bar and electrically connected with rails of another block whose rails are electrically connected and a source of electrical energy in such connection.

30. 10. A railway signal system comprising a

source of electrical energy electrically connected to the respective rails of one block, a solenoid electrically connected to the rails of said block and whose core is located in another block transversely of the rails thereof, and a second circuit mounted on a train and comprising a solenoid surrounding an axle thereof and having a polarized relay, a battery electrically connected to the armature of said relay and electrically connected through multiple arcs to the respective stops of said armature, and signal lamps in the respective arcs.

40. 11. A railway signal system comprising a source of electrical energy electrically connected to the respective rails of one block, a solenoid electrically connected to the rails of said block and whose core is located in another block transversely of the rails thereof, and a second circuit mounted on a train and comprising a solenoid surrounding an axle thereof, a battery and a polarized relay, a battery electrically connected to the armature of said relay and electrically connected through multiple arcs to the respective stops of said armature, and signal lamps in the respective arcs.
